UNITED STATES PATENT OFFICE.

ROBERT E. L. JANNEY, OF CHICAGO, ILLINOIS.

CARBURETER.

1,342,445.

Specification of Letters Patent.

Patented June 8, 1920.

Application filed December 7, 1915, Serial No. 65,541. Renewed July 8, 1918. Serial No. 243,965.

To all whom it may concern:

Be it known that I, ROBERT E. L. JANNEY, a citizen of the United States, residing at Chicago, in the county of Cook and State 5 of Illinois, have invented certain new and useful Improvements in Carbureters, of which the following is a specification.

My invention relates to carbureters, more especially designed for use in connection 10 with internal combustion engines, and has for its object to provide certain improvements in the admission and mixing of the liquid fuel and air to form the combustible mixture, as will be more definitely pointed 15 out and claimed hereinafter, reference being had to the accompanying drawings, in which:—

Figure 1 is a central vertical sectional view of a carbureter embodying my im- 20 proved construction, the parts being shown in such position that no fuel is being fed.

Fig. 2 is a similar view showing the parts 25 in such position as to feed a supply of fuel sufficient to provide a combustible mixture which will actuate the engine while running idle.

Fig. 3 is a bottom plan view of the same.

Fig. 4 is a detail vertical sectional view, 30 illustrating in diagrammatic form one feature of the invention.

Fig. 5 is a view similar to Fig. 1, partly broken away, but taken at a right angle to that of Fig. 1, and showing the valves in an open position.

Similar numerals of reference denote 35 corresponding parts in the several views.

In the said drawings, the reference numeral 1 denotes the mixture chamber of the carbureter, the same being shown slightly 40 tapered and connected with the usual manifold 1^a, and at its lower end with the usual fuel chamber 2, the latter, as shown in Fig. 3, being of substantially semi-circular form, and containing a conventional float 3 for 45 controlling the valve 4, which in turn controls the fuel supply passage 5.

Connected integrally with the mixture chamber 1 by means of a spider 6 is a casting 7, the same on its exterior surface con- 50 forming substantially to the interior configuration of the chamber 1, though spaced annularly therefrom, and being formed with a central opening 8, which is contracted upwardly to a point near the top of said casting and then somewhat abruptly

flared at 9 to the outer upper edge of said casting. Disposed at the bottom of the fuel chamber 2 and centrally of the chamber 1 is a base 10, extending upwardly toward said chamber 1 and screw threaded 60 exteriorly to receive the lower screw threaded end 11 of a tube 12, the same constituting a fuel supply jet, said portion 11 at its lower end being provided with a serrated flange 13, with which a spring arm 14, fixed 65 to the part 10, is adapted to engage to retain the two parts in any adjusted position with respect to each other. Mounted to slide upon the exterior of said tube 12 is a sleeve 15, tapered slightly at its upper end to form 70 a valve 16 adapted to fit the lower end of the central opening 8 in the casting 7, said sleeve being provided with trunnions 17 formed on opposite sides thereof. Mounted exteriorly of the sleeve 15 is an outer 75 sleeve 18, the same carrying at its upper end an annular valve 19 adapted to close the space between the lower end of the chamber 1 and the casting 7, as shown, said sleeve 18 being screw threaded exteriorly 80 at its lower end, upon which is fitted a screw nut 20 serrated on its outer face to be engaged by a spring arm 21, bolted to the exterior of said sleeve 18, for a purpose hereinafter to be described. 85

Pivoted at 22 in a depending portion of the carbureter integral with the chamber 1 is a bell crank lever whose upper bifurcated end 23 straddles the sleeve 18 and engages the oppositely projecting trunnions 17 on 90 sleeve 15, the latter projecting through slots 24 in said sleeve 18. The other arm 25 of said bell crank lever projects downwardly and is adapted to be engaged at its free end by certain of the operating parts herein- 95 after described. Also fixed to move with said bell crank lever is an operating lever 25^a adapted to be engaged at its free end by any suitable means, whereby said bell crank lever may be manipulated at will. 100 Disposed within the tube 12 is a pipe 26 having a discharge at its upper end at 26^a and formed conical at said upper end to correspond with the conical portion 27 of said tube 12, an annular conical space 27^a 105 being left between the upper end of said pipe 26 at the conical portion 27 of the tube 12, said pipe 26 opening into a chamber 28 at its lower end, closed by a screw plug 29, and from which leads a horizontal passage 110

30 communicating with an air supply tube 31. At 32 is shown a pipe leading from the fuel reservoir 2 into the space between the pipe 26 and the tube 12, whereby fuel will 5 be supplied to the interior of said tube 12. At its upper end above the pipe 26 said tube 12 is constricted to provide an atomizing duct 32^a, and above said duct widens into an oval expansion chamber 33, from which 10 in turn leads another constricted opening or duct 34 that communicates with the flared upper end of said tube.

Disposed in the pipe 31 is a rotary valve 35, controlled by an exterior lever 36, to 15 which is pivoted a rod 37, which passes loosely through an aperture 38 in the arm 25 of the bell crank. Disposed between said arm 25 and an adjusting nut 39 on the outer end of said rod 37 is a spring 40, while 20 upon the side of the valve 35 opposite to the lever 36 is a lug 41 adapted when turned to contact with a stop 42 on the lower end of the base 10, said lug having a set screw 43 adjustably to limit its closing movement. 25 Mounted in a suitable lug on that part of the carburetor in which the bell crank lever is pivoted is a screw 44 adapted to engage a projection 45 on the bell crank lever hub adjustably to limit the movement of said bell 30 crank lever in one direction.

In order to normally maintain the sleeve 18 and its valve 19 in the uppermost position shown, I provide a light spring 46 fixed to the fuel chamber and pressing against 35 the lower edge of said sleeve.

With the parts in the position shown in Fig. 1 there is the constantly open annular fuel supply passage 27^a between pipe 26 and tube 12, while the air jet passage 40 through valve 35 is also fully open, but inasmuch as the discharge of the air under this condition of adjustment through 27^a is somewhat greater than the capacity of the constricted duct 32^a, the requirement of the 45 latter will be satisfied completely by the air jet, and substantially no fuel will be fed with the air jet through said duct. However, a small quantity of fuel, depending upon the specific gravity of the same and the frictional resistance of the fuel passageway 27^a, will be entrained by the aspirating effect of the air passing from the jet. By shifting the bell crank lever slightly to the position 50 shown in Fig. 2, it results in a corresponding opening of the main air supply valve 16 and a proportionate closing of the valve 35 due to the rotation of the latter. This results in the cutting down of the jet of air, which in this position of the valve 35 is not 55 quite sufficient to satisfy the requirements of the duct 32^a, which results in the formation of a partial vacuum beneath said duct and a consequent satisfying of said vacuum by the suction with the air jet through the duct 60 of a small quantity of fuel, it being under-

stood that this position of parts is one which will supply enough fuel to provide an explosive mixture of a power sufficient to run the engine with no load thereon. Upon a further movement of the bell crank, the 70 trunnions 17 will engage the nut 20, whereby the sleeve 18 will also be moved downwardly causing the annular valve 19 to uncover the annular opening between the casting 7 and the chamber 1, admitting an additional supply of air to meet the mixture discharging from the passage 8, and this will be accompanied by a further closing of the valve 35 and a consequent further reduction in the air jet through pipe 26, which will 80 result in a proportionate increase in the amount of fuel delivered with said air jet to the duct 32^a, in a manner which readily will be understood.

The relative area and length of the atomizing duct 32^a are important. It must be of a length at least equal to its diameter in order to provide the annular frictional resistance. If too short, or of the Venturi type, it would not be suitable for the purpose. Preferably the area of this duct 32^a is slightly less than the area of the air discharge 26^a of pipe 26, so that no vacuum will be formed below said duct 32^a when there is a full supply of air admitted to pipe 26 95 through valve 35, and therefore there will be no flow of fuel.

By means of the screw connection between the lower portion 11 of the tube 12 and the base 10, said tube, which acts as the usual 100 needle valve, may be adjusted vertically with respect to the pipe 26 to vary the annular passage therethrough as desired, and this adjustment will be maintained through the engagement of spring 14 with the serrated 105 flange 13 on said portion 11.

The opening in the valve 35 disposed in pipe 31 is so arranged with respect to the lug 41 that when the adjustable set screw 43 thereon contacts with its stop 42, said 110 opening will not be completely closed, thus preventing the complete cutting off of air through the tube 26 by the normal movement of the bell crank lever. But when it is desired completely to cut off the air, in order that 115 more fuel may be drawn into the tube 32, for priming purposes, for instance, the rod 37 may be forced in the opposite direction to its normal movement until the passage through the valve 35 is out of register completely with the passage 30, thereby entirely cutting off the air.

On the sleeve 15 just below the conical valve 16, I have provided a supplemental annular valve 16^a, the same preferably being 120 formed integral with the sleeve 15. By employing this supplemental valve, I can if desired dispense entirely with the conical valve 16, as the supplemental valve 16^a will perform the closing function at that point. 130

The ring valve 19 controls the admission of the auxiliary air, and by the adjustment of the nut 20 at the lower end of the sleeve 18, the time of contact of the trunnions 17 there-
 5 with may be varied, so that the valve 19 can be opened simultaneously with the opening of the conical valve 16, or may be timed to open as soon as may be desired after the opening of said conical valve 16. By means
 10 of this adjustment the valve 16 may be fully opened, if desired, before the valve 19 controlling the auxiliary air supply begins to open. And, as will be hereinafter described, the connection between the sleeve 15 and the
 15 valve 35 controlling the air jet through tube 26 may be so adjusted that when the valve 16 is fully opened, the valve 35 will be brought to the limit of its closing movement.

The fuel after passing from orifice 32^a
 20 will receive an initial breaking up and mixing in chamber 33, and will then be contracted and discharged through orifice 34, where it will be met by the annular main air supply admitted by the downward move-
 25 ment of sleeve 15 and valve 16. This mix-
 ture then passes through the constricted dis-
 charge 8 from casting 7 and expands into
 chamber 1, and if the bell crank has been
 30 moved sufficiently to cause the trunnions 17
 to contact with and move the screw nut 20
 and its sleeve 18, thus opening valve 19, an
 annular supplemental supply of air between
 35 the casting 7 and the chamber 1 will be sup-
 plied to the mixture discharging from said
 casting, this supply of air increasing in pro-
 portion as the air through valve 35 is cut
 off and the demand upon orifice 32^a satisfied
 by a proportionately increasing amount of
 fuel.

40 I have illustrated in Fig. 4, diagram-
 matically the operation of my carbureter at
 this point. In said figure, I have shown a
 conventional central fuel supply tube 47,
 around which tube air is drawn between the
 45 same and the casting 7, and which dis-
 charges through the constricted opening in
 said casting, as shown by the arrows. A
 further supply of air is drawn upwardly
 between said casting 7 and the inner wall
 50 of said chamber 1, as also shown by the
 arrows, the result being that there is formed a
 vacuum space on the top of the flared por-
 tion 9 of the casting 7, the same gradually
 55 tapering upwardly, as shown by the dotted
 lines, until the meeting point of the mixed
 gas and air discharged from the casting 7
 and the air rising around said casting is
 reached. The tendency of the heavier par-
 60 ticles of the mixture, *i. e.*, globules of fuel,
 is to travel in the path of the least resist-
 ance. They, therefore, pass into this vac-
 uum area where they tend further to dis-
 tegrate and are then caught up and ab-
 sorbed by the surrounding jacket of air.
 65 It will also be observed that the top of the

tube 12 is shaped similarly to the top of the casting 7 at 9, so that a similar action on a small scale takes place upon the discharge of the mixed fuel and air through the orifice 34, a vacuum space being formed be-
 70 tween the same and the surrounding annular column of air which moves past the valve 16 when open. In using heavier fuels, it may be desired to increase the area of the flared portion 9 of the casting 7, as well as 75 the space above the tube 12 within the casting 7, which will create a greater vacuum area and consequently present a greater surface of surrounding air to the action of the mixture. The course of the mixture after 80 leaving the jet is from the center outward, and it will be noted that as no butterfly valve is used, and as the orifice of all the passageways point toward the intake mani-
 85 fold, the possibility of the fuel reaching the surrounding walls and lodging thereon is reduced to a minimum; before doing so it must pass through the vacuum area and the surrounding jacket of air.

90 My improved arrangement of parts re-
 sults in the production of what is substan-
 tially a combustible mixture passage com-
 prising three successive Venturi tubes, the
 first of which is formed by the upper por-
 95 tion of the expansion chamber 33, the con-
 stricted opening 34 and the top of said open-
 ing; the second one of which is formed by
 the character of the opening through the
 casting 7; and the third one of which is
 100 formed by the chamber 1 and its mani-
 fold 1^a.

It will be seen that with the various means
 of adjusting the different sources of supply
 the carbureter can be set to meet a certain
 condition where the bell crank lever is 105
 moved until the valve 16 has passed beyond
 the point where it controls the admission of
 air, and the rotary valve 35 has been closed
 as far as the set screw will admit, and that
 the valve 19 controlling the auxiliary air 110
 can then be still further opened without
 change as to the amount of fuel or air ad-
 mitted to the passageway 8. It is then pos-
 sible to suit varying atmospheric conditions
 to control the amount of auxiliary air ad-
 115 mitted to the passages without change as to
 the main air or fuel adjustment. Thus, the
 device is capable of adjustment for high and
 low speeds, and the throttling lever can be
 used to admit more or less air through the 120
 auxiliary air duct without change to the
 main air or the fuel supply.

Further, by arranging my supplemental
 air valve 19 as shown and described, I am
 enabled to operate the lever, when the en-
 gine is cold, to open the main air valve 16
 125 without opening the valve 19, thus produc-
 ing a rich mixture, and may retain that po-
 sition of parts until the engine has become
 thoroughly heated. With an auxiliary air 130

valve opening under suction this operation is impossible without employing auxiliary means for retaining said air valve closed.

It will be observed that all of the operations of my improved device are accomplished by a single lever, the initial movement of which opens the valve 16 and proportionately decreases the air jet through passage 26. A further movement of the lever still further opens the valve 16 and proportionately closes said air jet until the closure of the latter has reached its maximum, which is governed by the contact of the adjustable screw 43 with stop 42. With this position of the lever, the auxiliary valve 19 is also opened, the degree of opening thereof being dependent upon the adjustment of the screw nut 20, with which the trunnions 17 contact. If a further opening of said auxiliary air valve 19 is desired the same is produced by a further movement of the lever to the right, but which does not affect the air jet at 26, as the spring 40 by compression permits this further movement without affecting the rotary air valve 35. By this construction the fuel supply, the main air supply, and the auxiliary air supply are variably controlled through the operation of a single controlling device.

The present device provides a series of mixing spaces of the character shown, interposed at the juncture of the various elements together with means for causing the layers of the mixture positively and uniformly to flow from the inner to the outermost layers without the use of baffles. Furthermore, the fuel jet is provided with an expansion chamber ahead of the outlet of said jet, and in said jet air is admitted within the same for the purpose of controlling in the manner described, the supply of fuel through said jet, and for the further purpose of breaking up the fuel within an expanded portion of said jet into a partial mixture before it is admitted finally to the main air supply. It should be borne in mind that the admission of air within the fuel jet is solely for the purpose of controlling the supply of fuel and to assist in breaking up the same before it is admitted to the main and auxiliary air supplies. In other devices of this character, the admission of a greater amount of air, up to a certain point, means a greater amount of fuel also, whereas in my present device the admission of more air through the valve 35 means a reduced supply of fuel, and vice versa. While the air jet is placed in the center of the fuel supply for the purpose specified, it is obvious that this arrangement may be reversed, in which case pipe 31 would lead to the fuel supply and 32 to the air and controlling valve 35, the full opening of the jet in tube 26 being controlled by the conventional needle valve.

By placing the air jet in the center and surrounding it by a fuel supply, a greater area of fuel is exposed to the air in the preliminary breaking up of the fuel. In broad terms, this arrangement is not new, but in prior instances the fuel has left the control of the jet and combined with the air in a very much larger space, and is not again contracted before being introduced into the main air ducts.

It is especially desirable to prevent the fuel from lodging in air pockets or against the walls of the passages. The placing of the controlling valves below and ahead of the point where the fuel supply meets the main or auxiliary supply of air, together with the straight-away design of the various ducts, leaves a clear passage for the fuel after it is brought in contact with such supply of air and obviates the danger of its being diverted to the side walls of the passage, as is the case where a butterfly valve, or other means, is used in such passage beyond the point where the fuel has been admitted.

The construction of the device is such that all the air, together with the fuel supply, readily may be heated by fitting a casing, or hot air stove, to the open side and bottom of the front chamber.

This invention is an amplification of the construction shown in my prior application, filed Nov. 21, 1914, Serial No. 873,301, with such modifications, rearrangement and additions as have been found necessary best to adapt it to varying conditions.

Having thus described my invention, what I claim as new and desire to secure by Letters Patent, is:—

1. In a carbureter, a main air supply means, a fuel supply means of constant area, and a variable air jet for controlling said fuel supply in inverse ratio to said air jet.
2. In a carbureter, a main air supply means, a fuel supply means of constant area, a variable air jet for controlling said fuel supply, and a common means for controlling said main air supply and said air jet in inverse ratio to said air jet.
3. In a carbureter, a main air supply means, a supplemental air supply means, a fuel supply means, a controlling air jet for said fuel supply, and a common means for controlling said main and supplemental supplies and said air jet.
4. In a carbureter, a main air supply means, a supplemental air supply means, a fuel supply means, a controlling air jet for said fuel supply, and a common means for controlling said main and supplemental air supplies and said air jet, said means providing for a control of said main air supply and air jet without opening said supplemental air supply.
5. In a carbureter, a main air supply means, a fuel supply means of constant area,

- a variable air jet for controlling said fuel supply in inverse ratio to said air jet, and a receiving and discharge passage for said mixed fuel and air of an area less than that of said air at its maximum.
6. In a carbureter, a main air supply means, a fuel supply means of constant area, a variable air jet for controlling said fuel supply in inverse ratio to said air jet, a receiving and discharge passage for said mixed fuel and air of an area less than that of said air at its maximum, and means for varying said air jet to vary said fuel supply.
- 10 7. In a carbureter, a main air supply means, a fuel supply means, a controlling jet of air for said fuel supply, a receiving and discharging passage for said mixed fuel and air of an area less than that of said air jet at its maximum, means for varying said air jet to vary said fuel supply inversely, and a main air supply means surrounding said receiving and discharging passage.
- 15 8. In a carbureter, a main air supply means, a fuel supply means, a controlling jet of air for said fuel supply, a receiving and discharging passage for said mixed fuel and air of an area less than that of said air jet at its maximum, said main air supply means surrounding said receiving and discharging passage, and a common means for varying said air jet to vary said fuel supply inversely and for controlling said main air supply.
- 20 9. In a carbureter, a fuel supply means, a controlling jet of air for said fuel supply means, a receiving and discharging passage for said mixed fuel and air of an area less than that of said air jet at its maximum, a main air supply means around said passage, 40 a constricted mixing chamber receiving said supplies, and a supplemental air supply surrounding the discharge from said mixing chamber.
- 25 10. In a carbureter, a fuel supply means, a controlling jet of air for said fuel supply means, a receiving and discharging passage for said fuel and air of an area less than that of said air jet at its maximum, a main air supply means surrounding said passage, and a common means for reducing said air jet thereby increasing the fuel supply and for simultaneously increasing said main air supply.
- 30 11. In a carbureter, a fuel supply means, a controlling jet of air for said fuel supply means, means for varying said air jet to vary said fuel supply inversely, a main air supply means surrounding the fuel discharge, a supplemental air supply, and a common means for varying said air jet, said main air supply, and said supplemental air supply.
- 35 12. In a carbureter, a fuel supply means, a controlling jet of air for said fuel supply means, means for varying said air jet to vary said fuel supply inversely, a main air supply means surrounding the fuel discharge, a supplemental air supply, and a common means for varying said air jet to vary said fuel supply inversely, a main air supply means surrounding the fuel discharge, a supplemental air supply, and a common means for varying said air jet, said main air supply, and said supplemental air supply.
- 40 13. In a carbureter, a fuel supply means, a controlling jet of air for said fuel supply means, means for varying said air jet to vary said fuel supply inversely, a main air supply means surrounding the fuel discharge, a supplemental air supply means, a common means for varying said air jet, said main air supply, and said supplemental air supply, said means providing for a control of said fuel and main air supply without opening said supplemental air supply.
- 45 14. In a carbureter, a fuel supply means, a controlling jet of air for said fuel supply means, a receiving and discharging passage for said fuel and air of an area less than that of said air jet at its maximum, a valve for varying the capacity of said air jet, means for operating said valve, and adjustable means for preventing the complete closure of said valve.
- 50 15. In a carbureter, a fuel supply means, a controlling jet of air for said fuel supply means, a receiving and discharging passage for said fuel and air of an area less than that of said air jet at its maximum, a main air supply means surrounding said passage, a valve controlling said air jet, and a bell crank for moving said valve toward the closing position and for simultaneously opening said surrounding air supply.
- 55 16. In a carbureter, a fuel supply means, a controlling jet of air for said fuel supply means, a receiving and discharging passage for said fuel and air of an area less than that of said air jet at its maximum, a valve for varying the capacity of said air jet, a main air supply means surrounding said passage, a sleeve valve for controlling said main air supply, a mixing chamber receiving said fuel and air supplies, a supplemental air supply means surrounding the discharge from said mixing chamber, and a common means for controlling the several air supplies, to restrict the central air jet, and successively to increase the surrounding air supplies.
- 60 17. In a carbureter, a fuel supply means, a controlling jet of air for said fuel supply means, a receiving and discharging passage for said fuel and air of an area less than that of said air jet at its maximum, and an expansion chamber receiving the discharge from said passage.
- 65 18. In a carbureter, a fuel supply means, a controlling jet of air for said fuel supply means, a receiving and discharging passage for said fuel and air of an area less than that of said air jet at its maximum, and an expansion chamber receiving the discharge from said passage.

that of said air jet at its maximum, an expansion chamber receiving the discharge from said passage, and a constricted discharge from said chamber.

5. 19. In a carbureter, a fuel supply means, a controlling jet of air for said fuel supply means, a receiving and discharging passage for said fuel and air of an area less than that of said air jet at its maximum, an expansion chamber receiving the discharge from said passage, a constricted discharge from said chamber, an annular main air supply means around said discharge, a mixing chamber receiving the discharge from said chamber and said main air supply, and a constricted outlet to said mixing chamber.

20. 20. In a carbureter, a fuel supply means, a controlling jet of air for said fuel supply means, a receiving and discharging passage for said fuel and air of an area less than that of said air jet at its maximum, an expansion chamber receiving the discharge from said passage, a constricted discharge from said chamber, an annular main air supply means around said discharge, a mixing chamber receiving the discharge from said chamber and said main air supply, a constricted outlet to said mixing chamber, and an annular additional air supply means surrounding said outlet.

30. 21. In a carbureter, a fuel supply tube embodying an expansion chamber, a fuel atomizing jet discharging into said chamber, a similar jet discharging from said chamber into a main air supply, and means for supplying a mixture of liquid fuel and air to said first-named jet.

22. 22. In a carbureter, a tube constituting a fuel supply and having a discharge jet, and an annular air supply tube surrounding said fuel tube, the wall of said fuel tube at the discharge being formed to create an intervening mixing space between the discharge from said jet and said annular air supply tube, the inner wall of said annular air supply tube being in the form of a venturi, the throat of which is beyond said discharge jet.

45. 23. In a carbureter, a tube constituting a fuel supply and having a discharge jet, a

main annular air supply tube surrounding 50 said fuel supply tube, and a supplemental air supply tube surrounding said main annular air supply tube, the wall between said main and supplemental air tubes being formed to create an intervening mixing space 55 between the discharge from said main and supplemental air supply tubes, the inner wall of said supplemental air supply tube being in the form of a venturi, the throat of which is beyond the discharge from said 60 main air tube.

24. In a carbureter, a tube constituting a fuel supply, a controlling jet of air for said fuel supply, an expansion chamber for receiving said fuel and air, a discharge from 65 said tube, and a main annular air supply means surrounding said discharge, the wall of said tube at the discharge being thick enough to afford an intervening mixing space between said discharge jet and said 70 annular air supply and beyond the same, the inner wall of said annular air supply tube being in the form of a venturi, the throat of which is beyond said discharge jet.

25. 25. In a carbureter, a tube constituting a fuel supply and having a discharge jet, a controlling jet of air for said fuel supply, an expansion chamber for receiving said fuel and air, a main annular air supply tube surrounding said fuel supply tube, the wall of 80 said fuel supply tube at the discharge being thick enough to afford an intervening mixing space between said discharge jet and annular air supply and beyond the same, and a supplemental air supply means surrounding 85 said latter discharge, the wall of said air supply tube at the discharge also being thick enough to afford an intervening mixing space between said tube and said supplemental air supply and beyond the same, the inner wall of said supplemental air supply tube being in the form of a venturi, the throat of which is beyond the discharge from 90 said main air tube.

In testimony whereof I have hereunto set 95 my hand this 2nd day of December, 1915.

ROBERT E. L. JANNEY.
